UNITED STATES PATENT OFFICE.

ALLEN S. FONTAINE, OF NEW YORK, N. Y.

SPEAKING-TUBE.

SPECIFICATION forming part of Letters Patent No. 357,589, dated February 15, 1887.

Application filed October 22, 1885. Serial No. 180,588. (No model.)

To all whom it may concern:

Be it known that I, ALLEN S. FONTAINE, of the city, county, and State of New York, have invented a new and useful Improvement in 5 Speaking-Tubes; and I do hereby declare that the following is a full and exact description thereof, reference being had to the accompanying drawings, and to the letters of reference marked thereon, making a part of this specification.

My invention relates to the use of a single tube for establishing communication between one room and several others in such manner as that conversation may be carried on from 15 the one room with any one of the others without being overheard in the remaining rooms connected with the tube, and has for its object to insure more positively the desired result and to improve the devices for accomplishing 20 the same.

In the accompanying drawings, Figure 1 is a view in longitudinal section of a double-valve mouth-piece, and Fig. 2 a similar view of a single-valve mouth-piece, each provided 25 with an automatic locking device adapted to be opened by an electro-magnet. Fig. 3 is a perspective view, upon a greatly reduced scale, illustrating the arrangement of the electric switch-lever and call-bells in the office or 30 principal room with which my improved speaking-tube is designed to communicate. Fig. 4 is a diagram illustrating the electrical connections between the switch in the office and the several mouth-pieces connected with 35 the single speaking-tube leading to the office, and also the adaptation of a system of call-bells thereto. Fig. 5 is a diagram illustrating the method of placing a call-bell in the office, in a circuit to be closed at the mouth- 40 piece designated by said bell, and in connection with the switch in the office; and Fig. 6 is a diagram illustrating the modification of my invention, in which a system of levers, cranks, and wires is substituted for electrical 45 connections to operate the valve-locks at the several mouth-pieces.

A represents a speaking-tube extending from the office or room P to one or more of the remaining rooms in the building with 50 which it is desired to establish communication.

B B are mouth-pieces, which may be of the ordinary form of construction, fitted with a

valve, C, (see Figs. 1 and 2,) to close the same, the valve being made to shut automatically by the action of a spiral spring, D, in the hinge thereof, or by other equivalent form of spring device, and to be thrown open by means of an outer arm or lever, E. (Shown in dotted lines, Figs. 1 and 2.) The valve C, when closed, is automatically locked by means of a lever, F, (see Fig. 2,) pivoted at one end above the valve, and which is formed with an offset, a, near to its pivot end, adapted, as the lever drops, to engage the end of a bent arm, b, projecting from the upper end of the valve into 65 contact with said offset when the valve is closed. The fall of the lever is arrested so soon as it engages the arm of the valve by means of a stop, d. The faces of the offset a on the lever and of the opposed end of the arm b are beveled, so that as the valve closes the lever will be sufficiently lifted by the arm to allow it to pass, while the lever, dropping again in the rear of the arm, will lock it. The spring D is powerful enough to operate, in 70 closing the valve, to lift the lever automatically.

G is an electro-magnet placed above the free end of the lever F. The armature of the magnet is attached to the lever, so that when the 80 magnet is excited the lever will be lifted thereby far enough to release it from engagement with the valve C, leaving the latter free to be opened by the use of its handle-lever E.

H is a battery, and H' a wire leading from 85 one pole thereof to the magnets at each mouth-piece in the series communicating with the single tube A. The opposite pole of the battery is connected by a wire, H², with one end of a switch-arm, K, which, by its movement, 90 is made to connect said wire with either one of a series of wires, L L' L², &c., extending thence severally to each of said magnets, and to close thereby the circuit from the battery to either magnet.

The valve C, Fig. 2, may be provided with a whistle therein, which admits of being sounded only by a person blowing into the mouth-piece. A call-bell, O, is placed near to the mouth-piece B, in circuit with the electro-magnet G 100 and battery H, so that when the circuit is closed by the switch K, to operate the lever F and unlock the valve C, the bell will ring.

In the operation of the apparatus, if a per-

son at either mouth-piece B in the series connected with the single tube A—say No. 4—desires to communicate with the office P, he sounds the whistle in the valve, the number 5 of the room being indicated by any predetermined signal on said whistle. The attendant in the office thereupon turns the switch K to the proper button, 4, and thereby closes the circuit, including the magnet controlling the 10 lock of the mouth-piece valve in said room 4.

The lever F is thereby lifted to unlock the valve, so that the person at the mouth-piece may open it and speak through the tube. In the meantime, as the valves in all the other 15 mouth-pieces are automatically closed and locked, the conversation may not be overheard at any other mouth-piece, but remains private. To more effectually deaden the sound at each opening, a lining, S, Fig. 1, of felt or 20 other non-conducting material, may be combined with each valve or inserted therein.

To insure an immediate break of the circuit with the magnet so soon as the desired end of unlocking its valve is accomplished, the 25 switch-lever K is provided with a spiral spring, r, encircling its pivot, whereby, so soon as released, it will automatically fly back to an insulated point, o, Fig. 3, at which the circuit will be broken.

To more effectually prevent the possibility of the transmission of the vocal sounds in the speaking-tube, when it is in use, to the mouth-pieces which are closed, I combine with the hinged valve C at the mouth-piece a second 30 sliding valve, M, (see Fig. 1,) which is made to traverse the branch tube A', which leads from the mouth-piece B to the main tube A. For this purpose the mouth-piece is placed at the end of a straight horizontal length of tube, 35 A'', which is fitted across the branch tube A', at a right angle therewith, and so as to extend beyond it, as shown at A³, Fig. 1. The slide-valve M is fitted to play closely yet freely in the horizontal tube A'', so as to slide 40 back and forth over the mouth of the branch tube A', and it is connected with the upper part of the hinged valve C by means of a rod, R, jointed to each, and of such length as that when the valve C is closed the valve M covers 45 the mouth of the branch tube A', and when the valve C is opened it will push back the valve M beyond the mouth of the tube A' and thereby throw it open. The valve M is locked, when closed, by means of a pin or bolt, 50 S, arranged to drop through the wall of the tube A'' into a recess in the valve. This pin S is lifted and the valve unlocked, when required, by means of an electro-magnet, G', whose armature is attached to the pin S, and 55 which is placed in circuit with a battery, H, (see Fig. 3,) adapted to be closed, in manner as hereinbefore described, by the switch K in the office or principal room, P, to which the tube is led. As in this arrangement of double 60 valves for each mouth-piece a whistle in the outer valve, C, will be useless as a signal, I contemplate the use, in connection with each

mouth-piece in said system, of an electric annunciator-button, N, (see Fig. 1,) adapted to close the circuit of an annunciator of any approved construction, or of one of a series of electric call-bells, W W, (see Figs. 3 and 5,) placed in the main room P, one for each of the other rooms, by which the attention of the attendant in the main room P may be called in order 75 that he may unlock the mouth-piece valve to permit a use of the tube.

To prevent the person who may have used a mouth-piece from surreptitiously preventing the valve therein from closing after it has been 80 unlocked and opened for use, and thereby hearing the conversation thereafter held through the tube by other parties, I place an insulated metallic strip, T, longitudinally upon the periphery of the slide-valve M in position to 85 form a contact between the points V V, connected, respectively, with the battery-wire H' and a wire leading to the bell or annunciator-drop for said mouth-piece in the office, whereby whenever the valve for that mouth-piece 90 is open, even slightly, the circuit is closed for said bell or drop, so that the attendant in the office will know that the valve is open. To avoid any annoyance in the office, when a bell 95 W is used in this connection, from the ringing of the bell while the valve is open, a switch, Q, may be placed in the office to open the bell-circuit at the pleasure of the attendant.

I contemplate, likewise, causing the hinged valve C, where the hinged valve alone is used, 100 to actuate, whenever it is opened, an electric annunciator or call-bell, W, in the office by means of any of the well-known devices adapted for this purpose. I contemplate, furthermore, the substitution of levers 1 2, (see 105 diagram, Fig. 6,) each actuating an independent system of bell-cranks, U U U, connected by wires t t, extending from the office P to the bolt or catch locking each valve in the series 110 of mouth-pieces B B, communicating with the single tube A.

I claim as my invention--

1. In a system for communicating between the several rooms in a building and a central office or station by means of a single tube leading from said office or station and opening into each room, the combination, with the valved mouth-piece of the tube in each room, of a spring closing the valve in each mouth-piece, an automatic catch or lock for each valve, an electro-magnet operating, when excited, to release the catch or lock, a switch-lever at the central office or station, a series of insulated contact-points or buttons within reach of said lever, a battery one pole of which is connected with said switch-lever, a single conducting-wire leading from the battery to each magnet, and separate conducting-wires leading from each magnet to one of the several insulated contact-points within reach of the 125 switch-lever, whereby the mouth-piece in any one room may be unlocked by turning the switch-lever in the office to the appropriate contact-point for said room, substantially in 130

the manner and for the purpose herein set forth.

2. The combination, with the mouth-piece, of a speaking-tube constructed with a right-angled bend, and with a hinged valve controlling said mouth-piece, of a second slide-valve traversing the bend to open and close the tube, and a coupling-rod connecting the slide-valve with the upper end of the hinged valve, whereby the two valves are made to operate conjointly, substantially in the manner and for the purpose herein set forth.

3. The combination, with a speaking-tube, A', and a sliding valve, M, controlling the same, of the commutating or switch plate T, moving with the valve to come into contact, when the valve is opened, with the terminal points V V of wires in a circuit including the

battery and an annunciator-bell, and thereby close said circuit, substantially in the manner and for the purpose herein set forth.

4. The combination, with the pivoted valve C, controlling the mouth-piece B of a speaking-tube and the spring D actuating it, of an arm, b, projecting from the valve, a pivoted locking-lever, F, engaging said arm, and an electro-magnet, G, actuating the lever F, all substantially in the manner and for the purpose herein set forth.

In testimony whereof I have signed my name to this specification in the presence of two subscribing witnesses.

ALLEN S. FONTAINE.
